UNITED STATES PATENT OFFICE

115,173

DESIGN FOR A PORTABLE ELECTRIC HUMIDIFIER

Elmer A. Reid, Morrisville, Pa.

Application March 17, 1939, Serial No. 83,635

Term of patent 7 years

To all whom it may concern:

Be it known that I, Elmer A. Reid, a citizen of Great Britain, residing at Morrisville, in the county of Bucks and State of Pennsylvania, have invented a new, original, and ornamental Design for Portable Electric Humidifiers, of which the following is a specification, reference being had to the accompanying drawing, forming part thereof.

I claim:

The ornamental design for a portable electric humidifier, substantially as shown and described.

ELMER A. REID.
